UNITED STATES PATENT OFFICE

2,483,103

MAGAZINE PENCIL

Rinaldo Raimondi, Zurich, Switzerland

Application July 28, 1945; Serial No. 607,562
In Switzerland June 16, 1944

1 Claim. (Cl. 120—14.3)

1

The invention relates to a new and improved magazine pencil.

The main object of the invention consists in the provision of a pencil with a store for a plurality of leads of which any particular one may be brought into and out of its position for use. The leads may be of different colors or, if the same color, of different hardness.

In the accompanying drawing:

Fig. 1 is a sectional elevation of a pencil.

Fig. 2 is a cross-section on a larger scale.

Fig. 3 shows parts of the pencil in a side view.

Fig. 4 illustrates in sectional elevation a second embodiment of my invention.

Fig. 5 is a cross-section through a third example.

Referring to Figs. 1 to 3 of the drawing 3 indicates a tubular casing which is polygonal in transverse contour. Cooperating with the casing 3 is a barrel 5 having a slotted tapered end 11 projecting over the tip 2 of the casing 3, said tapered end forming a clamp 1 with sprung prongs for the lead 10. The upper end of the barrel 5 is rotatably and axially displaceably mounted in an annular bearing 14 fixed inside the casing 3. The upper end of the barrel 5 projects from the upper end of the casing 3 and carries a button 8 by means of which the barrel 5 may be axially displaced against the action of a spring 13 permitting the lower slotted end 11 to expand to release the lead 10. The latter may move freely in the barrel 5. By releasing the button 8 the barrel 5 is again forced into wedging engagement with the tip 2 of casing 3 the split end of barrel 5 gripping and holding the lead 10. Obviously, the same operations are necessary to renew the lead 10. The wall of the barrel 5 is provided with a slot 9 through which a lead 10 may pass. On the barrel 5 a tube 16 is rotatably mounted, the lower end of which projects into a bore of tip 2 of casing 3 and the upper end of the tube 16 abuts on the annular bearing member 14. The wall of the tube 16 is provided with an axial slot 17 through which a lead 10 may pass. The upper end portion of the tube 16 is also provided with a helical slot 22 extending half round the tube 16. Into the slot 22 projects a stud 18 of the barrel 5. By depressing the button 8 against the action of spring 13 the stud 18 of the barrel 5 forces the tube 16 to rotate until its axial slot 17 is in registration with the slot 9 of the barrel 5 and a lead 10 may pass through both slots 9 and 17.

The casing is provided with inwardly projecting division-walls 12 dividing the space be-

2

tween casing 3 and tube 16 into six chambers 15 each adapted to receive a lead 10.

By depressing button 8 to bring the slots 9, 17 into registration with each other and by turning the casing, the said slots 9, 17 may be brought opposite any one of the chambers 15 whereupon the lead 10 stored in said chamber 15 may be passed through the slots 9, 17 into the barrel 5 or inversely the lead 10 may be passed from the barrel 5 into a chamber 15 by simply turning the pencil until the lead falls by its own weight through the slots 9, 17. To place the slots 9, 17 exactly opposite any one of the chambers 15, the stationary ring 14 is provided with six teeth 7 corresponding in position to the chambers 15 of the casing 3. On said teeth 7 rests an annular member 6 having teeth 4 adapted to engage the notches between the teeth 7. Moreover, the member 6 is provided with a stud 26 projecting in a slot 34 of the barrel 5 running in axial direction. By turning the press button 8 the member 6 will partake on this turning, the spring 13 allows an axial displacement of the member 6 while the teeth 4 on the latter passes over the teeth 7. To show the position of the slots 9, 17 an index 23 is marked on the button 8, and the side walls of the casing 3 are provided each with a mark 24, the latter being of different colors, for instance black, red, blue, green, yellow, brown or the like. Instead of marks 24 of different colors the marks 24 may consist of numbers which indicate different hardness of the leads, when uni-colored leads are being used. To facilitate the entering of the leads 10 from the chambers 15 into the barrel 5, the end faces 19 and 20 are slanting.

In the position shown in Fig. 1 a lead 10 is in its position for use. The barrel 5 is forced home in the casing 3 by the spring 13. The slotted end 11 of the barrel 5 is constricted to cause the pincer 11 to grip the lead 10 and hold the same securely against axial displacement. To adjust the lead 10 or to remove it altogether so that another one might be inserted in the barrel 5, the pencil is turned so that its tip is uppermost, then the button 8 is pressed into the casing 3 causing the slots 9, 17 to be brought one above the other, and the lead 10 passes through said slots into a chamber 15. By turning the button 8, the slots 9, 17 are brought opposite the chamber 15 having the mark appropriated to the lead desired. A lead from the chamber 15 may fall into the barrel 5 through the slots 9, 17 by suitably turning the pencil. By releasing the button 8 the tube 16 is rotated automatically and closes slot 9 of the

barrel 5 the stud 18 moving in slot 22 by the action of spring 13.

In the construction shown in Fig. 4 the rotatably mounted tube 28 closing the chambers 15 and having the slot 17 to let the lead 10 pass is rigidly connected with the button 8 and with the pincer 1, 2, 11 for the lead 10. The tube 28 may be axially displaced against the action of spring 13 by pressing the button 8. Within the tube 28 the barrel 29 is rotatably mounted resting at 30 on the face of pincer 1 fastened to tube 28. The barrel 29 is provided with a groove 31 running in a screw line. Into said groove 31 projects a pin 32 forming part of an annular disk 33. The latter is rotatably arranged between a shoulder of the casing 3 and the fixed abutment ring 14. The pin 32 projects through an axial slot 34 of the tube 28 into the groove 31. By turning the button 8 the slot 17 of the tube 28 may be brought opposite any one of the chambers 15 and by pressing the button 8 in axial direction the barrel 29 will be turned by groove 31 and pin 32.

A lead 10 from any chamber 15 may pass into the barrel. While turning the tube 28 the ring 33 will be turned too by the pin 32 projecting through slot 34 of tube 28.

In both the examples shown in Figs. 1 and 4 the chambers 15 may be formed in a cylindrical casing 35 (Fig. 5) which is placed in an ornamental shell 3. The casing 35 may be turned with reference to the slot in the barrel by means similar to those shown in Figs. 1 to 4.

What I wish to secure by United States Letters Patent is:

In a mechanical pencil, a casing provided with a plurality of longitudinal lead storing chambers, a barrel extending slidably and rotatably through the entire length of said casing and having a manually operable button fixedly attached to one end thereof while the other end of the barrel is formed to constitute a lead gripping

pincer with a rearwardly tapered exterior engaging a complementary tapered bore in the adjacent end of the casing, said button extending into the other end of the casing and being axially 5 movable and rotatable therein, coupling means within said casing and comprising an annular bearing member with coupling teeth fixed to said casing and another annular coupling member having coupling teeth axially slidably mounted on said barrel but rotatable therewith, a compression spring between said button and said last named coupling member to urge the latter in engagement with the first coupling member and to maintain the button normally 10 in an extended position in which the lead gripping pincer is urged into the tapering bore of the casing to grip a lead held by said pincer, said barrel being provided with an axially extending slot adapted to be positioned upon rotation of the button into registration with any one of said 15 lead storing chambers of the casing, a tube provided with an axially extending slot and a helical slot rotatably mounted on said barrel and extending from a bearing shoulder in the tip end of the pencil to the annular bearing member which is fixedly attached in said casing, and a projection on said barrel extending into said helical slot to effect a rotative movement of said tube when said 20 button is depressed, whereby the axially extending slot in said tube is brought into registration with the axially extending slot in said barrel.

RINALDO RAIMONDI.
